W. HEINITZ

MECHANICAL MOVEMENT FOR STRAIGHT HOSIERY FRAMES

Filed March 5, 1924

Inventor
Woldemar Heinitz.

by Richard Scherpe
Attorney.

UNITED STATES PATENT OFFICE.

WOLDEMAR HEINITZ, OF CHEMNITZ, GERMANY.

MECHANICAL MOVEMENT FOR STRAIGHT HOSIERY FRAMES.

Application filed March 5, 1924. Serial No. 697,138.

To all whom it may concern:

Be it known that I, WOLDEMAR HEINITZ, a citizen of the German Republic, and resident of Chemnitz, Saxony, Germany, have **5** invented a new and useful Improved Mechanical Movement for Straight Hosiery Frames, of which the following is a specification.

This invention relates to a mechanical **10** movement for use in connection with straight hosiery frames; more especially, it relates to a driving gear for the thread guide bar of such frames. While hitherto the bar transmitting motion from the known **15** eccentric disk to the known thread guide bar has been reciprocated by the intermediary of a set of levers which rendered the service uncertain by reason of the elasticity of the levers, I employ a rotary gearing as **20** transmission means. The drawbacks resulting from the elasticity of the levers become particularly detrimental, if the hosiery frame is pretty long and when its working speed is increased. Both these circumstances **25** are of no consequence where my improved transmission gearing is used.

My invention is illustrated by way of example in the accompanying drawing which shows a front view of the gearing in question, the known thread guide bar and the **30** known means for rotating the eccentric disk being omitted.

35 *a* is the eccentric disk which is rotated by the shaft *a*¹. Behind the disk *a* is a reciprocating bar *b* which is guided by and between the guide members *e*. The bar *b* is provided with two rolls *c*, of which one is located on one side of the disk *a* and the other on the other side thereof, so that it **40** is reciprocated by the disk when this is rotated.

A portion *d* of the bar *a* is toothed so as to form a rack. This rack meshes with a pinion *g* which is firmly connected with a **45** larger cog-wheel *h*. The pinion *g* and the cog-wheel *h* are supported by an axle *f*.

Parallel to the bar *b* is arranged a reciprocating bar *m* which is guided in known manner and is the known member for transmitting the motion to the thread guide bar **50** (not shown). This bar is toothed at *l*, and

this rack *l* meshes with a pinion *k* supported on an axle *i* and meshing in its turn also with the cog-wheel *h*.

Supposing, the eccentric disk *a* rotates **55** in the direction indicated by its arrow, the bar *b* will be shifted to the left, as indicated by its arrow, then back to the right, then again to the left, and so on. At the same time, the *v* bar *m* will be reciprocated in **60** just the same manner, the only difference being that its speed is a little higher than that of the bar *b* owing to the pinion *k* being a little smaller than the pinion *g*. I wish it, **65** however, to be understood that the arrangement and combination of parts shown, as well as the dimensions thereof, for instance the diameters of the wheels forming the gearing is merely an example. The size of the pinions and of the cog-wheel may vary **70** according to the requirement in a given case, also the number of the wheels constituting the gearing may vary. The ratio of the transmission may be chosen as desired or required. At any rate, the motion **75** is transmitted from the bar *b* to the bar *m* without any elastic intermediary whereby the drawbacks hitherto experienced are perfectly obviated.

I claim:

80 1. A mechanical movement for use in connection with straight hosiery frames and apt to serve as driving gear for the bar transmitting motion to the thread guide bar of the frame, comprising, in combination, an eccentric disk, means to rotate it; a shiftable bar, and means to transmit the revolutions thereof to said bar so as to reciprocate it; another shiftable bar arranged parallel to the first-mentioned one at some **85** distance therefrom; teeth at the opposite edges of said bars; a pinion meshing with the teeth of the first-mentioned bar, a cog-wheel firmly connected with said pinion, and another pinion meshing with said cog-wheel, **90** as well as with the teeth of said other bar, for the purpose set forth.

95 2. A mechanical movement for use in connection with straight hosiery frames and apt to serve as driving gear for the bar transmitting motion to the thread guide bar of the frame, comprising, in combination,

an eccentric disk, and means to rotate it; a shiftable bar forming partly a rack, and means to guide it; motion-transmitting rolls attached to said bar at either side of said disk; another shiftable bar also forming partly a rack and being arranged parallel to the first-mentioned bar at some dis-

tance thereof; a pinion meshing with the rack-part of the first-mentioned bar; a cog-wheel firmly connected with said pinion, 10 and another pinion meshing with said cog-wheel, as well as with the rack-part of said other bar, for the purpose set forth.

WOLDEMAR HEINITZ.
